UNITED STATES PATENT OFFICE.

ALFRED B. JENKINS, OF WEST ORANGE, NEW JERSEY.

DESIGN FOR A VALVE-STEM.

SPECIFICATION forming part of Design No. 30,782, dated May 16, 1899.

Application filed April 19, 1899. Serial No. 713,687. Term of patent 14 years.

To all whom it may concern:

Be it known that I, ALFRED B. JENKINS, residing in West Orange, in the county of Essex and State of New Jersey, have invented and produced a new and original Design for Valve-Stems for Automatic Air and other Valves, of which the following is a specification, reference being had to the accompanying drawings, forming a part thereof, wherein—

Figure 1 is a view in perspective of the stem. Fig. 2 is a view in elevation thereof.

As shown in the drawings, the leading or material feature of my design consists of the

relatively short cylindrical section A, the relatively long cylindrical section A', and the interposed shoulder A².

Having described my invention, what I claim as new, and desire to secure by Letters Patent, is—

The design for a valve-stem as herein shown and described.

ALFRED B. JENKINS.
